Primary Examiner — Kevin K Rudzinski*Assistant Examiner* — Amber J Rabie(74) Attorney, Agent, or Firm — Schmeiser, Olsen & Watts LLP(57) CLAIM

The ornamental design for hoodie, as shown and described.

DESCRIPTION

FIG. 2.1 is a top, front, and left-side perspective view of the hoodie showing my new design;

FIG. 2.2 is a rear view thereof;

FIG. 2.3 is a left side view thereof;

FIG. 2.4 is a right-side view thereof; and

FIG. 2.5 is a front view thereof.

The broken lines show stitching on the article that form no part of the claimed design.

1 Claim, 5 Drawing Sheets(56)
